(73) Assignee: **Futai (USA) Inc.**, Edison, NJ (US)

Primary Examiner—Joel Sincavage

(*) Notice: This patent is subject to a terminal disclaimer.

(57) **CLAIM**

(**) Term: **14 Years**

The ornamental design for: charger for cellular phone battery, as shown and described.

(21) Appl. No.: **29/151,230**

DESCRIPTION

(22) Filed: **Oct. 31, 2001**

FIG. 1 is a front elevational view of a charger for cellular phone battery showing our new design;

(51) LOC (7) Cl. **13-02**

FIG. 2 is a rear elevational view;

(52) U.S. Cl. **D13/107**

FIG. 3 is a left side elevational view;

(58) Field of Search D13/107, 108; 320/107-115

FIG. 4 is a right side elevational view;

(56) **References Cited**

FIG. 5 is a top plan view;

U.S. PATENT DOCUMENTS

FIG. 6 is a bottom plan view;

D368,891 S * 4/1996 Kun D13/107
D373,993 S * 9/1996 Kettula D13/107

FIG. 7 is a perspective view of the charger; and,

OTHER PUBLICATIONS

FIG. 8 is a perspective view of the charger when the cover thereof is opened.

Rapid Battery Industrial Co Ltd MC608 Charger—www.asia.globalsources.com.*

The broken lines throughout the drawing figures are included for the purpose of illustrating environmental structure only and form no part of the claimed design.
